UNITED STATES PATENT OFFICE.

JOHN D. PUGH, OF BALTIMORE, MARYLAND.

HOT-METAL CAR.

Application filed June 4, 1918. Serial No. 238,199.

To all whom it may concern:

Be it known that I, JOHN D. PUGH, a citizen of the United States, and residing at Baltimore, Baltimore city, Maryland, have 5 invented certain new and useful Improvements in Hot-Metal Cars, of which the following is a specification.

The present invention relates to hot metal cars and more particularly to the type of 10 this class of cars having a tilting or dumping ladle.

The principal objects of the invention are to provide a car in which the spout of the ladle is constrained to follow a predetermined path in pouring; to provide means 15 for supporting the ladle which permits movement of the ladle transversely or laterally of the car and also permits tilting movement for pouring; to provide a construction 20 whereby the ladle is supported on the car while pouring; to provide means for limiting the travel of the spout when pouring; to provide means for locking the ladle in 25 normal or upright position; to provide a novel means for tilting the ladle; to provide means for guiding the spout in a predetermined 30 path in combination with the novel tilting means; and generally to improve the construction of this type of cars so that the ladle thereof may be tilted with a minimum effort. Other objects and features of novelty will be apparent from the description taken in connection with the drawings, in which:

Figure 1 is an end elevation of a car embodying the present invention;

Figure 2 is a side elevation of the frame or weight which may be used to tilt the ladle;

Figure 3 is an end view similar to Figure 1 illustrating another form of the invention;

Figure 4 is a half side elevation of the cars illustrated in Figures 1 and 3;

Figure 5 is an end elevation of another embodiment of the invention;

Figure 6 is a side elevation of the car shown in Figure 5;

Figure 7 is a detail showing a further 50 modification;

Figure 8 is a plan of the detail shown in Figure 7;

Figure 9 is an end elevation showing another form of the car in which the ladle is

supported by a single trunnion at each end 55 thereof;

Figure 10 is a detail of the structure used with the form illustrated by Figure 9;

Figure 11 is an end elevation of another 60 modification;

Figures 12 and 13 are details showing different positions of some of the parts of Figure 11 when the ladle is being tilted;

Figure 14 illustrates in end elevation a further modification having a novel locking 65 device for maintaining the ladle in normal or upright position;

Figure 15 is a side elevation of one of the locking devices; and

Figures 16 and 17 are end elevations of 70 the locking devices, Figure 16 showing the normal position of the same, and Figure 17 the position when the lock is rendered inoperative.

Referring to the drawings and more particularly to Figures 1 to 4 inclusive, the invention is illustrated in connection with a car having a body 20 supported on trucks in the usual manner. At each end of the body is a frame 21 the upper edge of which is 75 formed to provide a roller track. As shown, this track consists of a central portion 22 which is the lowest part of the track, end portions 23 which are substantially vertical, and inclined portions 24 connecting the portion 22 with the end parts 23. The ladle 25 which has the pouring spout 26 at each of the opposite sides thereof is supported on the tracks by means of roller trunnions 27 there being a pair of these trunnions at each 80 end of the ladle. As shown, these roller trunnions comprise a trunnion 28 rigidly secured to the end of the ladle and a ring 29 surrounding the trunnion, a roller bearing 30 being interposed between the ring and trunnion 85 whereby the ladle is supported for lateral and tilting movements with a minimum of friction.

It is one of the principal objects of the present invention to provide means for causing the spout to travel in a predetermined path when pouring. For this purpose a saddle 31 is secured to each end of the ladle and as shown each saddle comprises a pair of laterally projecting arms 32, each arm at the end thereof having a pin 33, the axis of which is substantially parallel to the axis 54 of the ladle. Furthermore, each pin is ar-

ranged substantially in alignment longitudinally of the car with a spout. Hence if the pins 33 at either side of the car are constrained to move in a predetermined path, 5 the adjacent spout will be caused to travel in a like or similar path. As clearly shown in Figures 1 and 3, the end surfaces 34 of the frame 21 are substantially vertical and plates 35 are arranged below the frame at 10 each end thereof so that the outer surfaces 36 of the same are flush with and form a continuation of the surfaces 34. It will be observed that the pins 33 in the normal position of the ladle or the upright position 15 thereof, are substantially in contact with the upper portion of the surfaces 34. Hence if there is a tendency for the ladle to tilt this tendency will be resisted by the pins 33 at one side of the ladle engaging with their 20 associated surfaces 34. Thus the prongs 37 between the track portions 23 and surfaces 34 in combination with the pins 33, constitute means for locking or maintaining the ladle in normal or upright position.

25 In the form of the invention illustrated by Figure 1 the ladle is adapted to be tilted by a downwardly acting force applied to the pins 33 on either side of the ladle. For this purpose a heavy frame is utilized consisting of the parallel uprights or legs 38 connected at their upper ends by a cross bar 39. The legs 38 are guided for vertical sliding movement by means of the bearings 40 and a ring 41 adapted to be engaged by the 35 hook of a crane is secured to the cross bar 39. The bearings 40 are disposed so that each of the legs 38 is spaced a slight distance from a surface 34 on the frame 21 of the car and each of these legs has a laterally 40 projecting lug 42 formed with a seat 43 adapted to engage the top of a pin 33. The weight of the frame is such that when it is allowed to descend it will push the pin 33 downward thereby tilting the ladle. It will be seen, as the pins 33 engage in seats 43 in the lugs 42, and as these lugs have vertical movement, the pins 33 will have a corresponding movement, any departure of the pin from this movement in a direction toward the center of the car being prevented 45 by the surfaces 34. Obviously, the seat 43 could be omitted and the pin be guided by contact with the leg 38 on one side and the surface 34 on the other. In this manner the spout will be caused to travel in a predetermined path, in this case a vertical path.

50 Normally the ladle is in upright position, as illustrated in full lines in Figure 1, the axis of the ladle being represented at 54. It will be noted that this axis is below the axes of the roller trunnions, and preferably the center of gravity of the ladle is also below the axes of the trunnions. For the purpose of tilting the ladle the heavy frame is 55 arranged at the place where the pouring is

desired. The car is run to this point and stopped when the surfaces 34 on the end frames 21 are opposite the legs 38. Then the heavy frame is allowed to descend, the lugs 42 engaging the pair of pins 33 on one 70 side of the ladle, thus exerting a downward force tending to tilt the ladle in a clock-wise direction, as viewed in Figure 1. During the first portion of the downward movement of the pins 33 the ladle will be simultaneously turned and pushed a little toward the left, as viewed in Figure 1. This movement toward the left will continue until the pins 33 have reached a position substantially horizontal with the right hand trunnions 75 80 Then further downward movement of the pins 33 will cause the ladle to move laterally toward the right until the right hand roller trunnions 27 reach the position 27' indicated in dotted lines. It will be observed that the downward movement of the pin 33 is limited by contact of the left hand trunnion 27 with the upright portion 23 of the roller track, this position of the trunnion being indicated at 27''. Further, the lateral and 85 tilting movements of the ladle have taken place on antifriction bearings so that the ladle is tilted with a minimum of effort. Again, it will be observed that during the 90 tilting of the ladle it has been supported entirely on the car body. The path of the axis of the ladle in pouring is represented by the dotted line a, Figure 1, the final position 54' of the axis being substantially vertically above the right hand track. As 95 100 the center of gravity of the ladle is generally lower, and certainly never higher than the axis, it will not move outside of the track far enough so that the moment of the weight of the ladle will be greater than the 105 moment of the weight of the car acting at its center of gravity. Consequently, as far as the center of gravity of the ladle is concerned it does not move to any position which will cause the car to overturn. When 110 the ladle is tilted to the dotted line position of Figure 1, the weight thereof is supported on the trunnions 27' and there is a further downwardly acting force due to the 115 weight of the frame engaging the pins 33, the position of these pins when the ladle is tilted being shown at 33'. The resultant weight of the ladle acting on the trunnions 27' and the downward force acting on pins 33' is outside of the track and consequently 120 there is a moment tending to tilt the car body. However this moment is resisted by the weight of the body and also by the frame, the legs 38 of which would prevent any substantial tilting movement of the 125 body.

130 Although an arrangement of parts for tilting the ladle in clock-wise direction as viewed in Figure 1 has been shown and described, it will be apparent that the ladle

could be tilted in a counterclock-wise direction by disposing the weighted frame at the left of the ladle as viewed in Figure 1. Thus either spout 26 may be guided for 5 pouring in a predetermined path.

The form of the invention illustrated in Figure 3 is the same as that shown in Figure 1 except that the ladle is adapted to be tilted by a different means which requires a 10 modification of the structure for causing the spout to travel in a predetermined path. The car, including the ladle and means for supporting the same, are the same in this form as in Figure 1. The ladle is provided 15 with the usual lifting lugs 52 adapted to be engaged by a crane hook 53. For the purpose of causing the spout to travel in a predetermined path, guide-ways for the pins 33 are provided, these guide-ways being 20 formed between the surfaces 34 and members 44 independent of the car each having a surface 45 parallel to and spaced from a surface 34. As shown, these surfaces 34 and 45 form a vertical guide-way for the 25 pins 33 so that as the ladle is tilted in a clockwise direction the pins 33 at the right hand side of the ladle will travel in a substantially straight vertical path. As the 30 spout is aligned with the said pins 33 it will also travel in a like path.

The movement of the ladle in tilting is the same as described in connection with Figure 1, the extent of tilting being limited by the left hand trunnion engaging the prong 37, this position being shown at 27" Fig. 3. The weight of the ladle when in full tilted position is supported from the crane hook 53, and also on the trunnion roller indicated at 27' Fig. 3. This latter roller is not 40 placed laterally from the car track far enough to overturn the car body, the weight of the body being more than sufficient to resist any turning moment.

In the form of the invention illustrated by 45 Figures 5 and 6, the ladle 25 is supported on frames 121 at the ends of the car body 20 by a pair of roller trunnions 27 at each end of the ladle. The track however is of different form comprising the central low portion 122 and the two curved end portions 123, although these end portions need not necessarily be curved.

Attached to the body of the car at the sides thereof and between the spouts and 55 the end frames 121 are the upwardly extending members 137 which have vertical outer surfaces 134 which, with the parallel surfaces 45 on the members 44, form guide-ways for the pins 33. In this form of the 60 invention the trunnions 27 merely support the ladle for movement transverse of the body during the first part of the tilting. During the greater part of the tilting movement the ladle is supported on lugs 46 carried by the prongs 137, these lugs being

adapted to form pivotal seats for the pins 33. During the tilting movement the ladle first moves slightly to the left as viewed in Figure 5 until the pins 33 are substantially horizontal with the right hand trunnions 27, 70 that is, until the pins engage the lugs 46. Thereafter further raising of the lifting lugs 52 tilts the entire ladle on the lugs 46 to the position illustrated in dotted lines in Figure 5. In this form of the car it will 75 be observed that the ladle is supported for free lateral and tilting movements, the pivotal support for the ladle during the tilting being entirely on the car, and the final position of the ladle being higher than in Figures 1 and 3 as the vertical movement of pins 33 is limited by the lugs 46. The prongs 137 could be located as described in connection with Figure 3, but as the pins 33 and lugs 46 must support the entire weight of 80 the ladle during the tilting, the prongs 137 are located on the frame so that the saddles 131 may be secured to the conical portions 47 of the ladle, thus permitting a more secure fastening of the saddles to the ladle. 85

Instead of forming guide-ways between the prongs 137 and members 44, they may be constructed entirely on the prongs in the manner shown by Figures 7 and 8. Thus the prongs 237 secured to the car body, in 90 the same manner as shown in Figure 6, may be made with a guide slot 248, the lower end of this slot forming a seat 246 for the pin 33 on the ladle.

In Figure 9 a modification is illustrated 95 in which the ladle 25 is supported by means of a single trunnion 27 at each end thereof on end frames 321 carried by the body 20 of the car. The upper edges of the frames 321 are each formed to constitute a track for 100 the roller trunnions 27. As shown this track consists of the central portion 322 which is substantially semicylindrical, the substantially vertical end portions 323 and the convex inclined portions 324 connecting the end portions 323 and the central portion 322. The spout is caused to travel in a predetermined path by the pins 33 which travel between the members 44 and the side surfaces 105 334 on the end frames 321.

In the operation of tilting the ladle, trunnions 27 first move to the left, then return to the seat 322, then advance up the inclined curved portions 324 of the tracks until they 110 finally rest against the end parts 323 thereof. The end parts 323, in connection with the side surfaces 334, thus act to limit the extent of tilting of the ladle. In returning the ladle to its upright position if the weight thereof is not sufficient to cause the trunnions to roll down the tracks, then the crane must be operated to raise the entire ladle upward so that the pin 33 will travel from its low position 33' to the upper end of the 115 guide-way to the position shown in Figure 120 125 130

10. Then pins 349 may be inserted in the openings 350 formed in the end frames, these pins acting as supports while the ladle is lowered to its normal position. The side 5 surfaces 334 in conjunction with the pins 33 act to maintain the ladle in its upright position in the same manner as described in connection with the other forms.

Figure 11 illustrates a ladle supported on 10 end frames 21 of the same form as described in connection with Figures 1 and 3. The ladle is also provided with saddles 31 having pins 33 cooperating with the side surfaces 34 on the end frames. In this modification 15 however in order to guide the spout in the desired predetermined path, the end plates 21 are provided with guide plates 451, two plates on each frame symmetrically arranged with respect to the vertical center 20 line thereof. Each end of the ladle has a pair of oppositely extending arms 452 each provided with a pin 453 arranged to engage in a guideway 454, formed in the guide plates. These guide-ways are constructed so 25 that as the pins 33 and spout on the associated side of the ladle travel downward, they will be constrained to move in a vertical path. Thus when the pins 33 have traveled to the 30 position substantially horizontal with respect to the right hand trunnions 27, the position of the right hand trunnion, pin 33, and pin 453, will be substantially as shown in Figure 12. During this part of the tilting the trunnions 27 have moved toward the left. 35 When the pins 33 reach the position shown in Figure 13, the right hand trunnion 27 will have returned to its original position, and the pins 453 will be at the lower end of the 40 guide-ways 454 as shown. During the remaining part of the tilting while the right hand trunnion 27 travels from the position shown in Figure 13 to the dotted line position of Figure 11, the pins 453 will move laterally in the guide-ways 454 to the dotted 45 line position 453' in Figure 11. Thus during the latter portion of the tilting movement, the ladle is guided by the pins 33 contacting with surfaces 36 on the plates 35. The extent of the tilting movement is limited 50 by the prongs 37 in the manner previously described.

In Figure 14, a hot metal car is shown in which the ladle 25 is supported by a single trunnion 27 at the opposite ends thereof resting on end frames 521, the upper edges of these frames being formed to constitute tracks for the roller trunnions. The ends of the ladle have the saddles 31 carrying 55 guide pins 33. The prongs 37 of the end frames however are not depended upon to lock the ladle upright, a novel form of locking device being provided for this purpose, and the prongs merely preventing horizontal 60 movement of the ladle. This locking device is shown in detail in Figures 15, 16 and 17,

and the ladle is provided with two of the devices on each side thereof secured to the lower portion thereof. As shown, a latch member 55 is pivotally secured to the ladle by means of the plates 56, the free end 70 thereof being positioned directly against a side member of the body 20 of the car. A pair of links 57 are pivotally mounted on the member 55 intermediate the ends thereof and the free ends of these links are pivotally 75 secured to a pin 58 carried by the links 59 in turn pivotally fastened to the ladle by plates 60. The arrangement of the links 57 and 59 is such that the member 55 normally occupies the position shown in Figure 16. In tilting the ladle the crane hooks engage 80 with the pins 58 thereby through the links 57 exerting a pull on the member 55 to swing it into the position illustrated in Figure 17, this movement being sufficient so that the 85 free end of the member 55 can pass the side member of the car body, a bevel 61 being provided for this purpose. These devices, therefore, and the prongs 37 and 137 engaging pins 33 in the other forms constitute 90 releasable means for normally locking the ladle so that it is maintained in upright position, and these means are rendered inoperative automatically by the tilting of the 95 ladle.

Although several specific embodiments of the invention have been described in detail, it is to be understood that the invention is not limited to these forms only but includes 100 modifications and changes which come within the scope of the appended claims.

Having thus described the invention what is claimed as new and desired to be secured by Letters Patent is:—

1. A hot metal car including in combination, a tiltable ladle having a spout, a car body, means supporting the ladle on the body for lateral and tilting movements, and means for causing the spout to travel in a predetermined path when tilting including a guideway similar to said path and a pin on the ladle aligned with said spout engaging said guideway.

2. A tilting hot metal car including in combination, a ladle having a pouring spout, a car body having a transverse track at each end thereof, said tracks being inclined upwardly from the center of the car toward the side having the spout, roller means supporting the ladle on the tracks for lateral movement, and means for guiding the ladle when tilting to cause the spout to travel in a substantially vertical path.

3. A tilting hot metal car including in combination, a ladle having a pouring spout, a car body, means for supporting the ladle for movement transversely of the body and for tilting movement, and means for guiding the ladle during tilting to cause the spout to travel in a substantially vertical path.

4. A hot metal car including in combination, a ladle having a pouring spout at each of the sides of the car, a car body, means for supporting the ladle for movement transversely of the body and for tilting movement toward either side, and means independent of said first means for positively guiding the ladle during tilting to cause either spout to travel in a predetermined path. 10
5. A hot metal car including in combination, a ladle having a pouring spout at each of the sides of the car, a car body, means for supporting the ladle for movement transversely of the body and for tilting movement toward either side, and means for guiding the ladle during tilting to cause either spout to travel in a substantially vertical path. 15
- 20 6. A hot metal car including in combination, a ladle having a pouring spout at each of the sides of the car, a car body, means for supporting the ladle for movement transversely of the body and for tilting movement toward either side, and means for guiding the ladle during tilting to cause either spout to travel in a substantially straight vertical path.
7. A hot metal car including in combination, a car body, a ladle having a pouring spout, means intermediate of the height of the ladle for supporting the same on said body for tilting, and means independent of said supporting means for positively guiding the spout in a predetermined path during tilting including a guide member on the said body and a cooperating member on the ladle. 30
- 40 8. A hot metal car including in combination, a car body, a ladle having a pouring spout, means for supporting the ladle on said body for tilting, a guide member on the body and means on the ladle cooperating with said member to cause the spout to positively travel in a predetermined path during tilting.
- 50 9. A tilting hot metal car including in combination, a ladle having a pouring spout, a car body having a transverse track at each end thereof, roller means supporting the ladle on the tracks for lateral movement, a vertical guide at the side of the car, and means on the ladle cooperating with the guide to cause the spout to travel in a substantially straight vertical path when tilting. 55
- 60 10. A hot metal car including in combination, a ladle having a pouring spout, a car body, means for tiltably supporting the ladle on the body, a guide at the side of the car, and means on the ladle slidably cooperating with said guide to cause the spout to travel in a predetermined path during tilting. 65
11. A hot metal car including in combination, a ladle having a pouring spout, a car body, means for tiltably supporting the ladle on the body, a member having a substantially vertical guiding surface at the side of the car, and means on the ladle cooperating with said surface to cause the spout to travel in a predetermined path during tilting. 70
12. A hot metal car including in combination, a ladle having a spout, a car body, means for supporting the ladle on the body for lateral and tilting movements, the center of gravity of the ladle being below said means, guide members at the side of the car, and means on the ladle slidably cooperating with said members to cause the spout to travel in a predetermined path during tilting. 75
13. A hot metal car including in combination, a car body, a ladle having a pouring spout carried by the body, means for supporting the ladle for tilting movement, a guide independent of said means, a pin on the ladle substantially aligned with the spout slidably associated with said guide whereby the spout is caused to travel in a path similar to the guide when the ladle is tilting. 80
14. A hot metal car including in combination, a car body, a tilttable ladle having a spout, means for supporting the ladle on the body during tilting, and means for guiding the spout in a substantially straight path including a pin in alignment with the spout. 85
15. A hot metal car including in combination, a ladle having a spout at one side, a car body, a frame at each end thereof, roller means supporting the ladle on said frame for lateral and tilting movements toward the side having the spout, and means for guiding the spout in a vertical path when tilting including a member on the spout side of the frame having a flat vertical surface and a pin on the ladle aligned with the spout in contact with said surface. 90
16. A hot metal car including in combination, a car body, a tilttable ladle having a pouring spout, means for pivotally supporting the ladle on the body when tilting, guide members comprising a member on the car and a member independent of the car, and means on the ladle cooperating with said members whereby the spout is caused to travel in a predetermined path during tilting. 115
17. A hot metal car including in combination, a tilttable ladle having a pouring spout, means for pivotally supporting the ladle when tilting, a guide member having a vertical surface, a second guide member independent of the car and spaced from the first member, and means on the ladle guided by said members whereby the spout is caused to travel in a predetermined path during tilting. 120
- 125
- 130

18. A hot metal car including in combination a ladle having a spout, a car body, a frame at each end thereof, roller means supporting the ladle on said frame for lateral and tilting movements, and means for causing the spout to travel in a vertical path when tilting including a member on the side of the body, a parallel member independent of the car, and a pin on the ladle guided by said members.
19. A hot metal car including in combination, a ladle having a spout, a car body, a frame at each end of the body having a concave track, roller means at each end of the ladle supporting the ladle on the tracks for lateral and tilting movements, a member at each side of the body having an exterior guiding surface, and a pin at each side of the ladle in contact with one of said surfaces, the members and pins being disposed so that the pins are at the top of their associated surfaces when the ladle is in upright position, whereby the ladle is held against tilting movement.
20. A hot metal car including in combination, a ladle having a spout at one side thereof, a car body, a transverse track at each end of the body, said track comprising a low portion centrally of the width of the car, a substantially vertical portion near the side of the car having the spout and an upwardly inclined portion extending from the low to the vertical portion, and rollers supporting the ladle on said tracks, the juncture of the inclined and vertical portions of the tracks being curved to form seats for the rollers during tilting of the ladle.
21. A hot metal car including in combination, a ladle having a spout at one side thereof, a car body, a transverse track at each end of the body, said track comprising a low portion centrally of the width of the car, a substantially vertical portion near the side of the car having the spout and an upwardly inclined portion extending from the low to the vertical portion, rollers supporting the ladle on said tracks, the juncture of the inclined and vertical portions of the tracks being curved to form seats for the rollers during tilting of the ladle, and means for causing the spout to move in a predetermined path.
22. A hot metal car including in combination, a ladle having a spout at one side thereof, a car body, a transverse track at each end of the body, said track comprising a low portion centrally of the width of the car, a substantially vertical portion near the side of the car having the spout and an upwardly inclined portion extending from the low to the vertical portion, rollers supporting the ladle on said tracks, the juncture of the inclined and vertical portions of the

tracks being curved to form seats for the rollers during tilting of the ladle, and guide means to cause the spout to move in a predetermined path.

23. A hot metal car including in combination, a ladle having a spout at each side, a car body, a concave track at each end of the body, a pair of roller trunnions at each end of the ladle supported by said tracks, and means for guiding either of the spouts in a predetermined path when the ladle is tilted.

24. A hot metal car including in combination, a ladle having a spout at each side, a car body, a concave track at each end of the body, a pair of roller trunnions at each end of the ladle supported by said tracks, and means for causing either of the spouts to travel in a predetermined path when the ladle is tilted including guide means, and a pin cooperating with said guide means, one of the last two parts being on the ladle.

25. A hot metal car including in combination, a ladle having a spout, a car body, means supporting the ladle on said body for lateral and tilting movements, releasable means maintaining the ladle upright, and means to guide the spout in a predetermined path, said releasable means being constructed and arranged to be automatically released as the ladle tilting means turns the ladle.

26. A hot metal car including in combination, a ladle having a spout at one side thereof, a car body, a transverse track at each end of the body, said track comprising a portion located centrally of the width of the car, a substantially vertical portion near the side of the car having the spout and a portion extending from the central to the vertical portion, and rollers supporting the ladle on said tracks, the juncture of the inclined and vertical portions of the tracks being curved to form seats for the rollers during tilting of the ladle.

27. A hot metal car including in combination, a ladle having a spout at one side thereof, a car body, a transverse track at each end of the body, said track comprising a portion located centrally of the width of the car, a substantially vertical portion near the side of the car having the spout and a portion extending from the central to the vertical portion, and rollers supporting the ladle on said tracks, the juncture of the inclined and vertical portions of the tracks being curved to form seats for the rollers during tilting of the ladle, and means for causing the spout to move in a predetermined path.

In testimony whereof I affix my signature.
JOHN D. PUGH.
